APPARATUS FOR MAKING BUNCH-YARN

Samuel Rushton Walsh, Valley Falls, R. I., assignor to H & B American Machine Company, a corporation of Maine

Application March 27, 1937, Serial No. 133,327

19 Claims. (Cl. 117—22)

This invention relates to twisting apparatus of the type employed for producing fancy yarns having bunches of differently colored threads formed at spaced intervals on the strand throughout its length, and in particular to yarn guiding devices for use with such apparatus; and has for one of its objects the provision of simple yarn guiding means which will effectively maintain the individual strands of bunch-forming material in positively spaced relation during the formation of the bunch yarn.

Another object of the invention is to provide a yarn guiding device which will permit the ready placing by the operator of the individual strands of the bunch-forming yarn into a definite spaced relation thereon and will maintain such spacing of the strands for forming bunches on the core yarn at definitely spaced intervals.

Another object of the invention is to provide a guide device of the above character which is devoid of adjustable guiding means for the bunch forming strands yet is adapted to permit the independent and selective positioning of the latter by the operator into separate pre-determined guiding positions whereby the distances between the bunches formed on the main core strand may be varied as desired.

Another object of the invention is to provide a yarn guide construction which will avoid the use of supporting and guiding members which act on the moving bunch-forming yarns to cause them to be deflected obliquely to their normal direction of feeding movement after leaving their respective feed rolls in being delivered at substantially right angles to the main yarn on which the bunches are formed.

Another object of the invention is the provision of a simple and inexpensive yarn guide construction which is capable of being readily applied to any existing bunch-forming twisting apparatus.

With these and other objects in view, the invention consists of certain novel features of construction, as will be more fully described, and particularly pointed out in the appended claims.

45 In the accompanying drawings:

Fig. 1 is a fragmentary front view looking at the head or driving end of a twisting machine and embodying one form of my invention;

50 Fig. 2 is a fragmentary side elevational view taken on the line 2—2 of Fig. 1;

Fig. 3 is an enlarged perspective view diagrammatically illustrating the relative operative relationship of the various parts of the twisting machine shown in Fig. 1 in connection with my novel 55 guide device for forming bunch yarn;

Fig. 4 is a perspective view, on enlarged scale, of one form of yarn guiding device constructed according to the present invention;

Fig. 5 is a perspective view of a modified form of yarn guide construction embodying my invention;

Fig. 6 is a perspective view of another modified construction of a yarn guiding device embodying my invention; and

Fig. 7 is a representation of a fragment of one variety of bunch yarn which may be produced by the use of a yarn guide construction embodying the present invention.

In the manufacture of bunch or novelty yarn in which one or more strands of differently colored yarns in addition to being twisted on the main core yarn are wound thereon at predetermined intervals to form bunches or nubs so as to give a fancy appearance thereto, it is customary to produce this particular type of yarn by 20 means of twisting apparatus involving the use of two sets of feed rolls for delivering the yarns, in which one set of rolls is intermittently operated to intermittently deliver the main core yarn to the receiving bobbin while the other set of delivery rolls rotates continuously to feed the bunch-forming yarns to the core yarn and be wound thereon during the intervals that the latter remains stationary to form the bunches. Heretofore, various yarn guiding constructions have 30 been employed over which the various strands of material are passed, and among such former constructions is one in which the core yarn is run through a wire guide eye or pigtail and the continuously fed bunch-forming yarns are delivered 35 obliquely on to the core yarn at a point immediately below the guide eye for the latter, which often results in the yarns becoming badly tangled. In another prior construction a series of 40 wide horizontal guide bars are utilized, one bar for each strand of yarn or thread and arranged in vertically spaced relation and extending substantially the entire length of the machine. However, this latter scheme is objectionable since by this arrangement the bars of the framework 45 are arranged very close together and when thus placed opposite and in front of the delivery or feed rolls for the strands of yarn so fill up the working space as to interfere with the efficient operation of the machine and to render it difficult 50 for the operators to have easy access to the delivery rolls and associated mechanism of the machine; and in order to overcome these prior difficulties I have found it to be of advantage to provide a yarn guiding device for machines of 55

this type wherein the main core yarn and a plurality of bunch-forming yarns are guided separately and independently to be delivered at predetermined points on the same side of the core 5 yarn where the bunches are simultaneously formed by winding the bunch forming yarns on the core yarn at each stoppage of the latter, with the yarns being twisted together between bunches, in which the bunches are formed without the 10 bunch forming yarns being bent, or caused to run laterally of or be deflected from their normal tangential direction of travel after leaving the bunch yarn feed rolls during their continuous delivery to and simultaneous winding on the main core 15 strand; and in order to attain these advantageous results I have further found it to be of advantage to provide a plurality of narrow upright yarn guiding devices adapted to be individually arranged in front of each set of delivery rolls for 20 the bunch forming yarns or thread for guiding and directing the same to the core yarn and at the same time locating the points at which the bunches are being wound; and for such purposes I have provided in one or more of the longitudinal 25 side faces a row of inwardly extending transverse slots for separately receiving the bunch-forming yarns; and in order to guide the main strand of core yarn I further provide guide means located 30 at the top end of my yarn guide device, and preferably in the nature of a depression which carries a smooth surface over which the core yarn passes and is supported thereby; and the following is a detailed description of several embodiments of this invention, illustrating the preferred means 35 by which these advantageous results may be accomplished:

With reference to the drawings, 10 designates a portion of the frame of a conventional twisting machine of the type used for making "novelty 40 yarn" and as shown is provided with the usual spindles 11 each carrying a yarn receiving bobbin 12 and being mounted and arranged for rotation on a stationary rail 13 which extends longitudinally of the machine. Disposed above the rail 13 and extending parallel therewith is the usual vertically reciprocable ring rail 14 on which is carried a row of rings 15 provided with suitable travelers 16 and through which rings the upper portions of the spindles 11 and bobbins 12 project. 45 A band or tape 17 passes around the pulleys 18 which are fast on the spindles 11 and thus serves to impart rotation thereto from the usual driving cylinder 19, as is of well-known construction in the art.

50 Mounted on the top end of the frame 10 is the usual creel board 20 whose top surface supports the end standards 21 for supporting the customary framework of bars and skewers of the standard creel and arranged for holding the rows of supply bobbins 22 and 23 respectively, from which the core and the bunch-forming yarns are fed.

The usual roller beam 25 of the machine frame is provided with a thread board 26 for each of the spindles 11 and having a pigtail thread guide eye 27 which is mounted above and substantially in alignment with the vertical axis of the spindle. The thread boards 26 are suitably hinged to the roller beam 25 to permit the thread board to be tipped back when desired.

55 Mounted on the top portion of the roller beam 25 are the customary roller stands 30 in which are journaled a plurality of sets of feed rolls for the core and the bunch-forming yarns, respectively. As shown in Fig. 2, two independent sets

of feed rolls are illustrated in which the front feed rolls for delivering the bunch-forming yarns B from the supply bobbins 23 are indicated at 31 and 32, while the rear rolls 33 and 34 act to feed the main core yarn C from the supply bobbins 5 22. The rolls 31 and 32 for the bunch-forming 10 yarns B are continuously driven, and the set of rolls 33 and 34 are operated intermittently to produce the bunch yarn by twisting, during the 15 interval of rest of the core yarn C, of the bunch-forming yarns B around the stopped strand of the core yarn. The head end frame support 35 and the box-like casing 36 contain the usual driving 20 mechanism of shafts, clutches and gearing (not shown) for continuously operating the rolls 31 25 and 32 for feeding the bunch-forming yarns, and for causing the intermittent rotation of the rear rolls 33 and 34 to feed and stop the core 30 yarn at desired intervals for twisting and winding the bunches or nubs thereon, such mechanism being of well-known construction and one preferably capable of control and of different speeds for varying the duration of the rest periods of the core yarn. The rolls 31, 32, 33 and 34 respectively have their directions of rotation as 35 indicated by the arrows in Figs. 2 and 3 of the drawings.

30 Guide eyes or pigtails 37, 38 and 39 respectively, located behind the various sets of rolls, as shown in Figs. 2 and 3, serve for directing the core and bunch-forming yarns to the respective sets of feed or delivery rolls. The bunch forming yarns B upon being unwound from the supply bobbins 22 are led through the guide eye 39, then pass 35 forwardly over and around the top roll 31, and after being wound about the latter roll one or more turns, the yarns B then pass between the rolls 31 and 32 and down over the back of the latter and thence under the lower roll 32, after 40 which they pass forwardly upwardly in a tangent to the roll 32 and continue in a straight line without deviation through the slots, to be hereinafter described, of the guide device embodying my invention, and emerge on the other side thereof to be wound as bunches on the main core yarn. 45 The main core yarn C as it is removed from the supply bobbin 22 passes through the guide eye 38, thence forwardly over and around the top roll 33, and after one or two wrappings thereon, it passes between the rolls 33 and 34 and around 50 and under the lower roll 34 from which it leaves in a direction tangent to the latter and is led upwardly and forwardly to pass over the usual horizontal bar and thence downwardly over and in front of the guide device, to be described, where the bunch-forming yarns are wound on the core yarn during its longitudinal movement 55 with respect to the guide.

50 In accordance with my invention I have provided a yarn guiding device for enabling the formation of a wide variety of patterns of bunch yarn to be easily and readily made in which my guide construction comprises a slender body member 40 made preferably of a long narrow piece of thin material, such as a strip of sheet metal or a stamping. If desired, the member 40 may comprise a strip of a molded composition, such as for example, vulcanized rubber, molded or pressed resinoid products, such as shaped bodies formed 60 partly or entirely of a phenolic resin, or a urea resin, or of the "Glyptal" type of resins or other common resinoid materials which are well-known as molding materials and capable of acquiring a smooth texture and of being matured 65 70 75

and set to a final hard solid condition under conditions of heat and pressure.

As shown in Figs. 1, 2 and 3 the yarn guiding device 40 is illustrated in its normal operating position in connection with a portion of a twisting machine in which I have shown the guide device as being mounted thereon in an upright position and secured to a horizontal bar 41 by means of screws 42 which pass through suitable holes 43 formed in the base portion of the guide body member 40.

In order to guide the main strand or core yarn on which the bunches or nubs are formed, I have provided on the top end of the guide member 40, a notch 45 which extends transversely across the end face of the guide body and at the opposite end thereof to that near which the holes 43 are formed. The notch 45 may be of any desired shape, as by being made either of partially rounded or of V-shape form, and it may also be located either coincident with or offset with respect to the longitudinal axis of the guide body 40 and at right angles thereto, the depth of the notch, of course, being sufficient to receive and confine the moving strand of core yarn so that the sides of the notch 45 properly guide the same in its longitudinal movement during the intermittent rotation of the core yarn delivery or feed rolls 33 and 34 respectively.

In order to separately guide the individual strands of bunch-forming yarns and to permit the spacing between the bunches or nubs to be changed or altered at will, I have shown in Fig. 4, one specific embodiment of my invention wherein in one of the longitudinal side faces of the guide body member 40 is provided with a row of elongated openings or narrow slots 46 for individually guiding the bunch-forming yarns, the slots 46 being preferably equally spaced from one another and extending transversely inwardly from the longitudinal edge 47 of the guide 40 and to a depth wherein the bottoms of the slots will extend beyond an imaginary longitudinal line which may be drawn along the front face of the guide body member 40 and passing through the notch 45. As thus formed, the openings 46 interrupt the continuity of the edge 47 to form a row of spaced teeth 48 along a substantial portion thereof. The openings or slots 46 may be arranged parallel with respect to each other or their longitudinal axes may be parallel and the opposite side walls of the teeth 48 tapered, if desired. However, each of the slotted openings 46 is formed of sufficient width for readily receiving an individual strand of the bunch-forming yarns, and one on each slot selected, so as to guide the same while maintaining the separate strands of yarn spaced at predetermined distances, depending on the selected slots, for forming the bunches on the core yarn at predetermined and definite intervals.

In Fig. 5, I have shown a modified form of my invention in which the guide comprises a body member 50 provided with a notch 51 for the core yarn in its top end, one of the longitudinal sides of the member 50 being formed with a row of diagonally extending slots 52 for guiding the bunch-forming yarns. The slots 52 are of generally parallel form and extend in a downward direction and toward the direction of travel of the core yarn to meet therewith at an angle. The bottoms of the slots 52 are in alignment and preferably offset to one side of a vertical line passing through the notch 51. Holes 55 are provided at the base of the body 50 near the opposite

end thereof from the notch 51 for mounting the device. It will be seen that the downwardly inclined arrangement of the slots 52 serves to maintain the strands of bunch-forming yarn in position and thus minimize any accidental loss therefrom through sidewise movement.

In Fig. 6 I have shown another modification of my invention in which a guide body 60 is provided with a plurality of oppositely arranged rows of slots 61 and 62 disposed in staggered relation at the opposite longitudinal edge portions of the body 60 to provide opposite groups of inwardly extending grooves from such edge portions for guiding and supporting the bunch-forming yarns, and that such a variation may be made without departing from the spirit and scope of the present invention.

In the use of any of my yarn guide constructions, as above described, the strands of the bunch-forming and the core yarns are delivered by their respective feed rolls 31, 32, 33 and 34 to the guide device 40, 50 or 60, as the case may be, the main core yarn C after it leaves its particular feed rolls, first passes upwardly across and over the top forward edge of the usual horizontal bar 55 which is positioned above the yarn guide. The core yarn then runs downwardly through the notch formed in the top of the guide device, then passes longitudinally downwardly across the front face of the guide body member 30 and through the guide eye of the pigtail 27 to the traveler 16, and thence to the bobbin 12 upon which it is wound. The bunch-forming yarns B leave their respective feed rolls along tangential lines and are led in a straight line from the underside of the latter to the guide device where they are inserted individually in one or more selected spaced slots 46, 52, 61 or 62, depending upon which form of my guide construction is employed, and the slots serve to separately support and guide the bunch forming yarns when they are being wound on the core yarn to form the bunches. In order to control the distance or interval of the spacing of the bunches formed on the core yarn, as desired, one can accomplish this result by simply selecting the desired or proper slots on the guide body in which the linear distance between the successive slots to be used corresponds to the desired spacing of the bunches to be formed on the composite or final bunched yarn. The revolutions of the traveler 16 act to twist the core and the bunch-forming yarn about the path of travel of the core yarn during simultaneous longitudinal movement of each, and also in the course of which the bobbin 50 operates to wind the bunch-forming yarns on the main core strand at each stoppage of the latter so as to form the desired bunches thereon.

As shown in Fig. 2 the guide 40, bars 41 and 55 may be supported at spaced positions by an L-shaped bracket 60, one arm of which is slotted, as indicated at 61, to receive a clamping bolt 62 and thus provide for adjustment of the guide 40 and the bars 41 and 55 towards and from the front line of feed rolls, and also align the core 65 yarn with reference to the guide eye 27.

It will be apparent that in accordance with this invention I have produced a yarn guiding device which is not only superior to the former constructions by reason of its simplicity but that it 70 obviates the necessity of individually adjustable guide elements for the bunch-forming yarns, as heretofore characterized certain of the prior devices, and in addition, it further avoids the unsightly framework previously utilized, thus leav- 75

ing the front portion of the machine clear and free from rows of bars which seriously interfere with the efficient production of the work since they tend to obstruct the accessibility of the various parts of the mechanism to the operator.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A yarn guide for twisting and like machines for making bunch yarn comprising a body having one edge slotted to provide a plurality of spaced openings disposed in a single row along said edge portion for selectively receiving and separately guiding one or more of the bunch-forming yarns.

2. A yarn guide for twisting and like machines for making bunch yarn comprising a slender elongated body having one of its longitudinal edges slotted to provide a plurality of spaced openings disposed along its length and extending transversely inwardly therefrom for selectively receiving and separately guiding one or more of the bunch-forming yarns.

3. A yarn guide for twisting and like machines for making bunch yarn comprising a thin slender body having spaced teeth at one edge thereof to provide a plurality of spaced openings along the length of said body for guiding one or more of the bunch-forming yarns.

4. A yarn guide for twisting and like machines for making bunch yarn comprising a thin slender body having spaced teeth on a longitudinally extending edge thereof to provide a plurality of spaced openings along the length of said body for receiving and guiding one or more of the bunch-forming yarns.

5. A yarn guide for twisting and like machines for making bunch yarn comprising a thin slender body having spaced teeth on a longitudinally extending edge thereof to provide a plurality of spaced openings along the length of said body and extending transversely inwardly from said edge for receiving and guiding one or more of the bunch-forming yarns.

6. A yarn guide for twisting and like machines for making bunch yarn comprising a thin slender body having spaced substantially parallel teeth on a longitudinally extending edge thereof to provide a plurality of spaced elongated openings along the length of said body and extending transversely inwardly from said edge for receiving and guiding one or more of the bunch-forming yarns.

7. A yarn guide for twisting and like machines for making bunch yarn comprising a thin slender body having spaced teeth on a longitudinally extending edge thereof to provide a plurality of spaced openings along the length of said body for receiving and guiding one or more of the bunch-forming yarns, and means at one end of said body for guiding the main core yarn.

8. A yarn guide for twisting and like machines for making bunch yarn comprising a thin slender body having spaced teeth on a longitudinally extending edge thereof to provide a plurality of spaced openings along the length of said body for receiving and guiding one or more of the bunch-forming yarns, and a notch formed at one end of said body for guiding the main core yarn.

9. A yarn guide for twisting and like machines

for making bunch yarn, comprising a long narrow body member adapted to be mounted in an upwardly extending position, means at the top end of said member for guiding the main core yarn, and a plurality of spaced guide members extending transversely of said body member and disposed one above another at one edge thereof, said guide members being located below and at generally right angles to said top core yarn guide means for guiding one or more of the bunch-forming yarns.

10. A yarn guide for twisting and like machines for making bunch yarn, comprising a long narrow body member consisting of a thin strip of material which is adapted to be mounted in an upwardly extending position, means at the top end of said body member for guiding the main core yarn, and a plurality of spaced guide members extending transversely of said body member and disposed one above another at one edge thereof, said guide members being located below and at generally right angles to said top core-yarn guide means for guiding a plurality of bunch-forming yarns.

11. A yarn guide for twisting and like machines for making bunch yarn, comprising a long narrow body member consisting of a thin strip of material which is adapted to be mounted in an upwardly extending position, means at the top end of said body member for guiding the main core yarn, and means on one edge and extending transversely of said guide body member and located below and at generally right angles to said top core-yarn guide means for guiding a plurality of bunch-forming yarns.

12. A yarn guide for twisting and like machines for making bunch yarn, comprising a long narrow body member consisting of a thin strip of material which is adapted to be mounted in an upwardly extending position, means at the top end of said body member for guiding the main core yarn, and spaced means on one of the longitudinal edges and extending transversely of said guide body member and located below and at generally right angles to said top core-yarn guide means for guiding a plurality of bunch-forming yarns.

13. A yarn guide for twisting and like machines for making bunch yarn, comprising a long narrow body member consisting of a thin strip of material which is adapted to be mounted in an upwardly extending position, a notch at the top end of said body member for guiding the main core yarn, and means on one edge and extending transversely of said body member and located below and at generally right angles to said top core-yarn guide means for guiding a plurality of bunch-forming yarns.

14. A yarn guide for twisting and like machines for making bunch yarn, comprising a long narrow body member consisting of a thin strip of material which is adapted to be mounted in an upwardly extending position, a notch at the top end of said body member for guiding the main core yarn, means on one edge and extending transversely of said guide body member and located below and at generally right angles to said top core-yarn guide means for guiding a plurality of bunch-forming yarns, and means near the opposite end of said body to that carrying the notch for mounting the body in an upright position.

15. In a twisting or like machine for use in making bunch yarn and having a receiving bobbin for the final bunch yarn and pairs of rolls for feeding each yarn, one pair of said rolls being

arranged for feeding the core yarn intermittently to said bobbin and another pair of rolls which feed the bunch-forming yarns continuously to the core yarn, of a guide element for the core and bunch-forming yarns comprising a long narrow member adapted to be mounted with its longitudinal axis extending in an upright position, said guide element being disposed between the feed rolls for the bunch-forming yarns and said receiving bobbin for the final bunched yarn, the top end of said guide element being notched for guiding the main core yarn, and the body part of said member having a row of transversely extending teeth at one edge thereof, the openings between which selected teeth serve for guiding one or more of the individual bunch-forming yarns.

16. In a twisting or like machine for use in making bunch yarn and having a receiving bobbin for the final bunch yarn and pairs of rolls for feeding each yarn, one pair of said rolls being arranged for feeding the core yarn intermittently to said bobbin and another pair of rolls which feed the bunch-forming yarns continuously to the core yarn, of a guide element for the core and bunch-forming yarns, comprising a long narrow member adapted to be disposed in an upright position between the feed rolls for the bunch-forming yarns and said receiving bobbin for the final bunched yarn, one edge of said guide

element being transversely slotted for receiving and guiding one or more of the bunch-forming yarns.

17. A yarn guide for twisting and like machines for making bunch yarn comprising a member having one edge slotted diagonally inwardly 5 therefrom to provide a plurality of spaced openings for selectively receiving and guiding one or more of the bunch-forming yarns.

18. A yarn guide for twisting and like machines for making bunch yarn comprising an elongated member having its opposite longitudinal edges transversely slotted to provide a plurality of groups of spaced openings along a portion of each of said edges of the member, the 15 openings of said groups being adapted for selectively receiving and separately guiding one or more of the bunch-forming yarns.

19. A yarn guide for twisting and like machines for making bunch yarn comprising a body member 20 adapted to be mounted in an upstanding position, said body having a plurality of spaced guide elements extending transversely thereof and disposed one above the other in a single row, when so mounted, to provide a plurality of spaced 25 openings for receiving and guiding one or more of the bunch forming yarns.

SAMUEL RUSHTON WALSH.
